COMBINED CLEAVER, TENDERIZER, AND
SAW OR SIMILAR ARTICLE

Samuel L. Gerson, Wilmington, Del.

Application March 24, 1953, Serial No. 24,181

Term of patent 14 years

(Cl. D11—1)

To all whom it may concern:

Be it known, that I, Samuel L. Gerson, a citizen of the United States, residing in Wilmington, New Castle County, Delaware, have invented a new, original, and ornamental Design for a Combined Cleaver, Tenderizer, and Saw or Similar Article, of which the following is a specification, reference being had to the accompanying drawing, forming a part thereof, in which:

Figure 1 is a view in perspective of a combined cleaver, tenderizer, and saw showing my new design;

Figure 2 is an enlarged side view of the combined cleaver, tenderizer, and saw shown in Figure 1;

Figure 3 is a top edge view of the combined cleaver, tenderizer, and saw;

Figure 4 is a front end view of the combined cleaver, tenderizer, and saw; and

Figure 5 is a sectional view of the combined cleaver, tenderizer, and saw taken on the line 5—5, Figure 2.

I claim:

The ornamental design for a combined cleaver, tenderizer, and saw or similar article, substantially as shown.

SAMUEL L. GERSON.
